Des. 205,336
Patented July 19, 1966

205,336

CARPET UNDERLAY

Donald G. Rowland, Woodbridge, William F. Conway, Huntington, and James M. Green, Naugatuck, Conn., assignors to The B. F. Goodrich Company, New York, N.Y., a corporation of New York

Filed Oct. 14, 1963, Ser. No. 76,952

Term of patent 14 years

(Cl. D92—4)

FIG. 1

FIG. 2

FIG. 3

FIG. 1 is a plan view of a carpet underlay embodying our new design;

FIG. 2 is a sectional view taken on the line 2—2 of FIG. 1; and

FIG. 3 is another plan view thereof.

We claim:

The ornamental design for a carpet underlay, as shown.
